Inventor.

Giulio Cesare Cappa.

By Henry Worth atty.

UNITED STATES PATENT OFFICE.

GIULIO CESARE CAPPA, OF TURIN, ITALY.

INTERNAL-COMBUSTION ENGINE WITH INCLINED CYLINDERS.

Application filed March 5, 1925, Serial No. 18,276, and in Italy March 12, 1924.

This invention has for its object improvements in internal combustion engines of the V type and is characterized by the fact that the crankshaft is perfectly symmetrical and is provided with the driving gear of the transmission shaft in the symmetry plane, so that the main parts of the engine are operated by the said driving gear.

Owing to this arrangement, the advantage 10 is obtained of reducing the torsional stress of the shaft and the deflection due to said stress. Moreover the construction of the crankshaft and cam shaft is simpler than in ordinary engines as said members may without 15 any inconvenience be constructed in two parts.

The perfectly symmetrical form of the engine increases its facility of adaptation.

The annexed drawing shows by way of 20 example and diagrammatically the invention applied to an 8 cylinder aviation engine.

Fig. 1 is a longitudinal section thereof on line A—B of Fig. 2.

Fig. 2 is a diagrammatic view of the driving gears situated in the plane of symmetry indicated by the line C—D of Fig. 1.

Referring to the drawing, the reference 1 denotes the crankshaft, that may be divided into two parts connected together through a gear 2, actuating by means of a reducing wheel 3, the driving shaft 4 of the propeller.

The same wheel 2 operates by means of a series of pinions 5, 6 the secondary shafts 7 and auxiliary or cam shafts 8 for actuating the sparking plugs, the oil pumps and other auxiliary devices of the engine.

On the wheel hub 3 are arranged the pinions 9 actuating, through the intermediary pinions 10 and wheels 11, the valve gear shafts 12.

It will be seen that in some cases the pro-

peller shaft 4 may actuate also the valve gear; in this case it will be provided with cams thus substituting the shafts 12, moreover the crankshaft instead of four cranks 43 as shown, may be provided with any number thereof, as the invention may be used in connection with engines having any number of cylinders and also in other constructions when convenient.

What I claim is:

An internal combustion engine of the V-type comprising a two-part crank-shaft mounted in the plane bisecting the angle formed by the two rows of the engine cylinders, a single gear in the middle cross plane of the engine connecting the two parts of the crank-shaft, a driving-shaft mounted above the crank-shaft parallel to and in the same vertical plane of the latter, a single reducing gear centrally mounted on the driving-shaft in mesh with the gear on the crank-shaft, separate secondary-shafts mounted in said bisecting plane below the crank-shaft and parallel to the latter, a separate pinion 65 on the inner end of each secondary-shaft in mesh with the gear on the crank-shaft, separate auxiliary-shafts mounted below the secondary-shafts in said bisecting plane, separate pinions on the inner ends of the auxiliary shafts in mesh with the pinions on the secondary-shafts, separate valve-gear shafts mounted above and parallel to the driving shaft in said bisecting plane, pinions on the inner ends of the valve-gear shafts, gear 70 teeth formed on the hub of the reducing gear on both sides of the latter, and pinions meshing with said gear teeth and the pinions on the inner ends of the valve gear shafts.

In testimony that I claim the foregoing as 80 my invention, I have signed my name.

GIULIO CESARE CAPPA.
